US00D822499S

(12) United States Design Patent (10) Patent No.: US D822,499 S
Lalier et al. (45) Date of Patent: * Jul. 10, 2018

(54) CONTAINER

(71) Applicant: Conopco, Inc., Englewood Cliffs, NJ (US)

(72) Inventors: Gregory Lalier, Brookfield, CT (US); Slavica Cesare, Trumbull, CT (US); Lauren Alicia Shute, Seattle, WA (US)

(73) Assignee: Conopco, Inc., Englewood Cliffs, NJ (US)

() Term: 15 Years

(21) Appl. No.: 29/588,749

(22) Filed: Dec. 22, 2016

(51) LOC (11) Cl. 09-01

(52) U.S. Cl. USPC ..... D9/682

(58) Field of Classification Search

USPC ..... CLAIM

The ornamental design for a container, as shown and described.

DESCRIPTION

FIG. 1 is a front perspective view above of a container showing our new design;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof; and,
FIG. 7 is a bottom plan view thereof.

The broken lines in FIG. 7 are included for the purpose of illustrating the portion of the package that forms no part of the claimed design.

1 Claim, 6 Drawing Sheets
